UNITED STATES PATENT OFFICE,

JOHN J. COBB, OF GRAND RAPIDS, MICHIGAN.

IMPROVEMENT IN FENDERS FOR SLEIGHS.

Specification forming part of Letters Patent No. **158,201**, dated December 29, 1874; application filed October 31, 1874.

To all whom it may concern:

Be it known that I, JOHN J. COBB, of the city of Grand Rapids, Kent county, Michigan, have invented a new and useful Improvement in Wings to Fancy Cutters and Sleighs, of which the following is a specification:

The object of my invention is to produce a wing of metallic substance that may be pressed out of a single piece of metal, that shall be easily adjusted, strong, durable, light, and susceptible of a perfect finish by paint and varnish, and that can, without great bulk, weight, or expense, be readily shipped, each piece packing to the other in such a manner that when packed the bulk is one solid package, the wing to be of such form as to admit of easy ingress to and egress from the cutter or sleigh, as shown by drawing.

In drawing, C represents runner of cutter or sleigh; B, the metallic wing, and A A the flanges to attach the same to the runner by screws or otherwise. When the wing is made of thin material, in the outer edge of the wing

may be inserted a wire for strengthening the same, as in the upper edge of a tin pan or pail. The ends of the said wire may be bent in form of a loop and a screw, bolt, or other manner of fastening the same to the runner, may be inserted in said loops to make the fastening more firm.

I am aware it has been customary to extend the dash-boards of cutters outside of the runners in order to form a wing or fender. Such extension of dash-board I disclaim any desire to secure patented; but

What I claim to have invented, and desire patented, is—

The metallic wing B, with flanges A A, divided near the center of wing B, and each flange bent at right angles with the convex portion of the same, substantially as and for the purposes set forth.

JOHN J. COBB.
